CLAIM

The ornamental design for the fireplace hook, as shown and described.

DESCRIPTION

FIG. 1 is a perspective view of a first embodiment of the fireplace hook showing the design, wherein there are two sections;

FIG. 2 is a front elevational view thereof;

FIG. 3 is a rear elevational view thereof;

FIG. 4 is a left side view thereof;

FIG. 5 is a left side view thereof;

FIG. 6 is a bottom plan view thereof;

FIG. 7 is a top plan view thereof;

FIG. 8 is a perspective view of a second embodiment of the fireplace hook showing the design, wherein there are three sections;

FIG. 9 is a front elevational view thereof;

FIG. 10 is a rear elevational view thereof;

FIG. 11 is a left side view thereof;

FIG. 12 is a left side view thereof;

FIG. 13 is a bottom plan view thereof; and,

FIG. 14 is a top plan view thereof.

1 Claim, 8 Drawing Sheets
